CLAIM

The ornamental design for a T-shaped cap for a medical injector, as shown and described.

DESCRIPTION

FIG. 1 is a perspective view of a T-shaped cap for a medical injector in accordance with the present invention;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a perspective view thereof shown engaged with an injector in accordance with the present invention.

The broken line representing the injector shown in FIGS. 6-8 represents disclaimed subject matter and forms no part of the claimed design.

1 Claim, 8 Drawing Sheets(56)
